UNITED STATES PATENT OFFICE.

CHARLES W. SLEEPER, OF ISLAND POND, VERMONT.

DEVICE FOR FEEDING SHEETS OF TIN.

SPECIFICATION forming part of Letters Patent No. 393,082, dated November 20, 1888.

Application filed May 10, 1888. Serial No. 273,430. (No model.)

To all whom it may concern:

Be it known that I, CHARLES W. SLEEPER, a citizen of the United States, residing at Island Pond, in the county of Essex and State 5 of Vermont, have invented a new and useful Device for Feeding Sheets of Tin, of which the following is a specification.

My invention relates to improvements in tin-feeding mechanism, by which the tin is fed 10 to a point beyond the feeding device and during its forward movement is prepared for soldering by having its edges rolled smooth and to the proper shape and supplied with a suitable flux. I attain these objects by means of 15 the mechanism illustrated in the accompanying drawings, in which—

Figure 1 is a vertical central longitudinal section of the device. Fig. 2 is an end view of fluxing device. Fig. 3 is a part front view of 20 rollers enlarged to show shapes of faces. Fig. 4 is a front view of device complete. Fig. 5 is a plan of the same.

My invention is composed of a bed, A, provided with slots or ways A' A', two adjustable sides, A² A³, four crimping-rolls, a¹ a² a³, a fluxing device, a⁴, guides d d, a sliding block, d², and cross-bar d³, a shelf, or table, B, and various rests and guides, which will be described in their proper places. The adjustable 25 sides A² A³ are secured to the bed A by means of the bolts a a, and are provided with the crimping-rolls a¹ a² a³, secured by means of shoulder screws or pins, upon which they are 30 secured. The rolls a² a³ have faces shaped as shown in Fig. 3, while the rolls a¹ a¹ have flat faces.

The fluxing device a⁴ is secured to the adjustable side A², and consists of a metal piece, a⁴, with a narrow groove, a⁵, through its 35 tire length and opened at one end to receive the tin. The piece a⁴ is also provided with a hole at a⁶, into which the flux is fed from an ordinary lubricator by means of the tube b'. The groove a⁵ is intended to hold the liquid 40 flux by capillary attraction. The sides A² A³ are provided with rests c c, to support the ends of the sheets of tin, and guides c' c' c' c', to facilitate the placing of the sheets of tin in the proper position to be fed forward. The 45 shelf or table B is supported by two uprights, B' B', secured to the bed A by the bolts B² B². A spring-guide, B³, is riveted to the shelf B. The guides d d are secured to the bed A by

suitable screws. The sliding block d' is fitted between the guides d d, and is provided with 55 an ear, d², to which the necessary mechanism for moving the same will be attached. The cross-bar d³ (the ends of which are shaped as shown in Fig. 1) is secured to the sliding block d'. 60

In operating the device the pieces of tin, E, to be fed are placed upon the shelf or table B. The adjustable sides A² A³ are moved upon the bed A to the proper position to guide the sheets of tin as required. The sheets of tin, E, 65 are placed (one at a time) between the adjustable sides A² A³, so that the ends will rest upon the rests c c and the center upon the guides d d. As the sliding block d' moves forward, the ends of the cross-bar d³ engage with 70 the edge of the sheet of tin and press it forward between the rolls a¹ a² a³, in passing through which all lumps and nicks are pressed smooth, and the end which passes between the rolls a² a³ is slightly crimped, so that when 75 formed about a cylinder it will remain close to the same instead of forming a tangent with its circumference. As the tin is pressed forward the end which passes between the rolls a² a³ enters the groove a⁵ of the fluxing device 80 a⁴ and is moistened upon both sides by the flux in said groove. The spring-guide B³ holds the sheet of tin down upon the guides d d, so that it may be fed accurately between such working parts as are provided for further operations. 85

What I claim as my invention, and desire to secure by Patent, is—

1. The combination of the bed A, the adjustable sides A² A³, the rolls a¹ a² a³, and the 90 fluxing device a⁴, substantially as described, and for the purpose set forth.

2. The combination, with the above-described bed A, sides A² A³, rolls a¹ a² a³, and fluxing device a⁴, of the guides d d, the sliding block d', and the cross-bar d³, substantially 95 as described, and for the purpose set forth.

3. The combination, with the bed A, the sides A² A³, rollers a¹ a² a³, and fluxing device a⁴, of the shelf or table B, substantially as 100 described, and for the purpose set forth.

CHARLES W. SLEEPER.
